UNITED STATES PATENT OFFICE

JOSEPH STURM, OF CANTON, OHIO, ASSIGNOR, BY MESNE ASSIGNMENTS, TO REPUBLIC STEEL CORPORATION, OF YOUNGSTOWN, OHIO, A CORPORATION OF NEW JERSEY

DRAWER LOCKING MECHANISM

Application filed November 5, 1928. Serial No. 317,181.

This invention relates to drawer-locking mechanism for desks and the like. In sheet metal desks of the type now generally in commercial use, the locking of all the pedestal drawers is usually effected by the closing of the center or knee-space drawer. Heretofore it has been necessary, in order to have access to one or more of the pedestal drawers, to manually pull the center drawer out, a sufficient distance to permit the pedestal drawer locking mechanism to disengage the pedestal drawers. The precise distance which the center drawer must be pulled out, to permit such operation, varies to such an extent in different desks, that only a "cut and try" method will ensure the positive unlocking of the pedestal drawers.

Frequently, regardless of the distance the center drawer is pulled out, the pedestal-drawer locking mechanism does not disengage the pedestal drawers, due perhaps to corrosion or disuse of such mechanism. In such cases, it is necessary to close the center drawer violently in an effort to loosen the "sticking" pedestal drawer locking mechanism, with the result that both the desk and the locking mechanism are liable to be damaged.

It is a primary object of the present invention to obviate the above mentioned difficulties, by providing a locking mechanism for desks and the like, which will assure positive locking and unlocking of the pedestal drawers.

Another object of the invention is to provide a locking mechanism for desks and the like, which will be of rugged construction, simple in operation, and will permit of easy assembly and disassembly.

These and other objects of the invention will become more readily apparent in the course of the following description of a preferred embodiment of the invention, taken in connection with the accompanying drawings wherein

Fig. 1 is a fragmentary plan view of a sheet metal desk, with the top removed to more clearly show the locking mechanism;

Fig. 2 is a cross section through the desk taken on the line 2-2 of Fig. 1, and showing

in elevation the pedestal drawer locking mechanism in locking position;

Fig. 3 is a fragmentary cross section through the desk taken on the line 3-3 of Fig. 1, and showing the center drawer in locked position;

Fig. 3a is a view similar to Fig. 3, and showing the center drawer in unlocked position;

Fig. 4 is a fragmentary cross section through the desk, taken on the line 4-4 of Fig. 1;

Fig. 5 is a perspective view of one of the pedestal drawer locking hooks; and Fig. 6 is a perspective view of one of the pedestal drawer locking hook springs.

Referring more particularly to the drawings, wherein like reference characters are used to designate like parts, the desk includes pedestal units 1, 1, a center drawer 2 and a top 3. The pedestal units being exactly alike, the pedestal drawer locking mechanism will be hereinafter generally described with reference to only one of the units.

The pedestal units 1, 1, include legs 4 at each corner thereof, and knee-space sides 5, suitably secured to the two inner legs of each unit. Each pedestal unit contains drawers 6, to the sides of each of which are rigidly secured, as by welding, suspension channels 7, which are slidably mounted in suspension channels 8. Suspension channels 8 are secured, as by welding, at each end to legs 4, and intermediate their ends to vertically disposed Z bars 9, which are in turn secured as by welding, to the knee-space side 5, and to the outer side (not shown) of each pedestal unit respectively. Clips 10, consisting of channel shaped portions 11, and offset tongues 12, are secured, as by welding, near the rear end of those suspension channels 8, which are adjacent the knee-space side 5, these clips serving a purpose to be presently described.

The center drawer 3, is provided at both sides with suspension channels 13, which are rigidly secured thereto as by welding. Suspension channels 13 are slidably mounted in suspension channels 14, which are secured,

as by welding, at each end to legs 4, and saddles 15, which are in turn secured as by welding to knee-space sides 5.

Secured as by welding, near the top and 5 to the rear of knee-space sides 5 are saddles 16 and 17, provided in their intermediate portion with holes 18 and 19 respectively. A hole 20 is provided in each knee-space side 5. Holes 18, 19 and 20 are coaxial and serve 10 as bearings for a crank 21. Each crank 21 consists of a body portion 22, and an offset pin 23. The opposite end of the body portion 22 is threaded and cut away on opposite sides thereof to form an approximately rectangular portion 24.

Non-rotatably mounted on the rectangular portion 24 of the crank 21, is an arm 25 having a bifurcated end, consisting of furcations 26 and 27. The arm 25 is prevented from 20 lateral movement by means of a nut 28. As will be noted in Fig. 3, suspension channels 13 are longer than the center drawer 2, and are provided, near their rear extremities with pins 29.

25 Suspended from the offset pin 23 of crank 21 is a lock bar 30, which is guided for vertical reciprocal motion in the channel shaped portions 11 of clips 10, and is restrained from excessive lateral movement by means of pins 30 31, secured to the clips.

The normal downward pull of gravity on the bar 30, is assisted by a tension coil spring 32, which is secured at its upper end to the bar 30, and at its lower end, to one of the pins 35 31. Downward movement of the bar 30 is limited by means of extrusions 33, as will be later described.

Pivotedly secured at spaced points on the lock bar 30, are pedestal drawer locking 40 hooks 34, each of which includes an upwardly and backwardly sloping edge 35, and a seat 36. The hooks 34 are normally held in a position at right angles to the lock bar 30, as shown in solid lines in Fig. 2, by means of 45 wire springs 37, but are prevented from moving upwardly past the position shown in solid lines, by means of extrusions 38, of lock bar 30, which abut the lower rear edges of the hooks 34.

50 As will be noted in Fig. 2, suspension channels 7 are longer than the pedestal drawers 6, and are provided near their rear extremities with pins 39.

55 The center drawer 2 is further provided with a key lock 40, having a bolt 41, which may be projected upward and in the rear of a strike 42, secured to the dependent apron 43 of the top 3.

60 The operation of the aforesaid locking mechanism is briefly as follows:

With the center drawer 2 locked, as shown in Fig. 3, the pin 29 bears against the furcation 27 of the arm 25, and through the intermediary of the crank 21, holds the lock bar

30 in its uppermost position, as shown in solid lines in Fig. 2.

If the pedestal drawers are closed, such as the two upper drawers in Fig. 2, the hooks 34 will engage the pins 39, and hold these drawers in closed or locked position, as shown. If when the center drawer 2 is closed and locked, one of the pedestal drawers happens to be open, such as the bottom drawer in Fig. 2, it may be locked by merely pushing it in to the position indicated in dotted lines, at *a*, the pin 39 in such closing movement sliding on the rearwardly and upwardly sloping edge 35 of the hook 34, and forcing the hook to swing downward on its pivot 75 against the pressure of the spring 37 as shown in dotted lines at *b*.

To unlock all of the drawers of the desk it is only necessary to retract the bolt 41 of the lock 40. With the center drawer thus 80 released, the coil spring 32, which is under considerable tension, pulls the lock bar 30 downwardly to the position shown in dotted lines in Fig. 2 at *c*, and the latter is prevented from further downward movement by the 85 abutment of extrusion 33 against the upper edge of the channel shaped portion 11, of the uppermost clip 10. This action brings all the hooks to the position indicated in dotted lines at *d* and unlocks the drawers 6. 90

At the same time, the downward movement of the lock bar 30, swings the crank 21 to the position shown in dotted lines at *e*, the arm 25 assuming the position shown in Fig. 3a. Furcation 27 bears against the pin 29 100 and thereby forces the center drawer 2 outwardly to the position shown in this figure. The weight of the bar 30, supplemented by the tension of the coil spring 32, is sufficient to move the center drawer 2, to the position 105 shown in Fig. 3a even if the drawer is heavily loaded.

Should the coil spring 32 break, or become disengaged from the lock bar 30, or the lock bar 30 stick to such an extent that the spring 110 115 is not capable of pulling it downward, the pedestal drawers may be unlocked by pulling the center drawer 2 out. Pulling the center drawer out causes the pin 29 to bear against furcation 26 of the arm 25, thus 115 swinging the crank 21, and moving the lock bar 30 to its lowermost position.

It will be seen that provision has been made, not only for positive locking, but also for positive unlocking of the pedestal 120 drawers, and that in normal use of the desk, the necessity for manually pulling the center drawer out to any predetermined position to unlock the pedestal drawers is entirely obviated.

It will be understood that the pedestal drawer locking mechanisms for both pedestal units, are alike, and that they are operated simultaneously by the center drawer.

It will be further understood that the lock- 130

ing mechanism herein described is not necessarily limited for use in a desk, but may be used in connection with the locking of other drawer systems, and that various changes in the locking mechanism, per se, may be made without departing from the invention, the scope of which is defined in the appended claims.

Claims:

- 10 1. In a locking mechanism for a plurality of drawers, yieldable means placed in position by the closing of one of said drawers to permit the locking of the other drawers, said means including a bar having a plurality of hooks resiliently mounted thereon, and means operable by the drawer in its opening movement to positively unlock the other drawers.
- 15 2. A structure as defined in claim 1, in which the hooks are pivotally mounted on the bar, and spring means are provided for normally holding the hooks in their uppermost pivotal position.
- 20 3. A structure as defined in claim 1, in which the last-named means includes a crank, rotation of which in one direction is adapted to move the bar to drawer unlocking position, and a pin on said drawer adapted to cause rotation of said crank in said direction.
- 25 4. In a locking mechanism for a plurality of drawers, drawer locking means movable to locking position by the closing of one of said drawers, said means being yieldable to permit the closing and locking of the other drawers while said one drawer is closed, means for positively opening said one drawer when it is unlocked, and means operable by the opening of said one drawer to positively unlock the other drawers.
- 30 5. A structure as defined in claim 4, in which the first-named means includes a bar having a plurality of hooks pivotally mounted thereon and spring means normally holding the hooks in their uppermost pivotal position.
- 35 6. A structure as defined in claim 4, in which the second-named means includes a pin on said drawer, a crank adapted to be rotated in one direction to bear against said pin and force the drawer open, and a coil spring having connections for rotating the crank in said direction.

In testimony whereof I affix my signature.
JOSEPH STURM.
